UNITED STATES PATENT OFFICE.

GEORGE W. DAUM AND GEORGE W. SHIVELEY, OF JEANNETTE, PENNSYLVANIA.

DESIGN FOR A VEHICLE-TIRE.

46,359.

Specification for Design.

Patented Sept. 8, 1914.

Application filed July 30, 1914. Serial No. 854,189. Term of patent 14 years.

To all whom it may concern:

Be it known that we, GEORGE W. DAUM and GEORGE W. SHIVELEY, both citizens of the United States, and both residing at Jeannette, in the county of Westmoreland and State of Pennsylvania, have invented a new, original, and ornamental Design for Vehicle Tires, of which the following is a specification, reference being had to the accompanying drawing forming part thereof.

Figure 1 is a top plan view of a portion of the tire, and Fig. 2 is an elevation thereof.

We claim:

The ornamental design for a vehicle tire as shown.

GEORGE W. DAUM.

GEORGE W. SHIVELEY.

Witnesses:

A. H. PRICE,

R. G. BAUM.
